UNITED STATES PATENT OFFICE.

WILLIAM GABRIEL, OF DETROIT, MICHIGAN.

RAILWAY-TIE.

No. 908,766.

Specification of Letters Patent.

Patented Jan. 5, 1909.

Application filed January 2, 1908. Serial No. 408,987.

To all whom it may concern:

Be it known that I, WILLIAM GABRIEL, a citizen of the United States of America, residing at Detroit, in the county of Wayne 5 and State of Michigan, have invented certain new and useful Improvements in Railway-Ties, of which the following is a specification, reference being had therein to the accompanying drawings.

10 This invention relates to reinforced cement tie construction, and consists in the matters hereinafter set forth, and more particularly pointed out in the appended claims.

In the drawings, Figure 1 is a view in perspective of a tie embodying features of the invention, with portions broken away for a clear view. Fig. 2 is a view in longitudinal section of the tie. Fig. 3 is a view in section on or about line $\alpha-\alpha$ of Fig. 1. Fig. 4 is a 15 plan view of a section of track equipped with the ties. Fig. 5 is a view in detail of a rail chair or clamp. Fig. 6 is a view in detail of a reinforcing rod brace. Fig. 7 is an 20 enlarged view in detail showing manner of securing a rail to a tie. Fig. 8 is a view in detail showing engagement of a tie by a rail chair. Fig. 9 is a view in detail of an anchor 25 for a reinforcing bar. Fig. 10 is a view in detail in longitudinal section of the end portion of a tie showing disposition of anchoring means. Fig. 11 is a view in detail of a 30 piece of a rail suspension wire.

Referring to the drawings, the tie body is a substantially rectangular hollow shell 1 of 35 concrete or like cementitious material, with sloping ends and sides reinforced by a suitably shaped main frame 2 wound with a double layer of wire 3 applied to form a diamond mesh. Secondary reinforcing rods 40 4 and 5 outside the windings bent into N or M shapes are embedded in the top and bottom wall of the shell. U-shaped sheet metal anchor plates 6 are inserted in the bends of the rods, and have tongues 7 cut out of their 45 bodies which are bent up more or less to form ledges which support the rods at a predetermined distance above the windings, while the tie is being molded. Corresponding upper and lower anchor plates may be 50 connected, if desired, by upright rods 8, as seen in Fig. 10. Intermediate supports 9 each consisting of a strip of sheet metal bent or folded into an X prevent the rods sagging

between the ends while the concrete is being tamped around them. The lower face of the 55 tie has a pair of longitudinal ballast retaining grooves 26. Notches 10 are formed at each end for engaging a crow-bar when it is desired to shift the tie laterally, and hand grips 11 are provided in each end face. 60

At the places where the track rails cross, the body of the tie is solid and a pair of broad transverse ribs 12 are formed thereon with extended, slightly rounded ends 13 which have cross-gains or square grooves 65 14 on their upper faces. The ribs are each reinforced by a pair of outwardly convex, perforated sheet metal wings 15 whose lower ends are connected to the main frame and whose upper divergent arms 16 interlock with 70 corresponding notches in a templet 17 of wood, fiber, or the like. A winding of suspension wires 18 in substantially parallel relation holds the wings in place, and passes through the grooves 14. To prevent the suspension wires from chafing against the templet corners, round rods 19 are inset therein for bearings for the wires. The latter are coated with a layer 20 of soft enamel paint 75 or the like, so that when they are embedded 80 in the concrete they may move longitudinally under stress as the concrete cannot grip them tightly. The space in the grooves 14 below the suspension wires is filled with a yieldable or plastic material 21 which permits the suspension wire to sag between the upper rounded ends of the wings and the templet rods 19. 85

A rail chair 22 is seated in each groove 14 in which it is removably secured by a pair 90 of dependent arms 23 embracing the tie rib, the ends being inbent as by tapping with a spike maul, to engage inclined grooves 24 in the sides of the ribs. A pair of oppositely disposed undercut lugs 25 on the upper sides 95 of the chair are so disposed that a rail base will just drop between them when the tie is at right angles, and grip the rail when the tie is slightly oblique, as shown in Figs. 4 and 7. The rails are thus carried directly 100 on the suspension wires which afford yielding support so that the pounding and jarring of the rails does not tend to disintegrate the cement. The suspension wires are not liable to shear off as they are not in contact 105 with angular corners.

Obviously details of construction may be varied without departing from the spirit of the invention and I do not limit myself to any particular form or arrangement of parts 5 save as set forth in certain of the appended claims.

What I claim as my invention is:—

1. A track tie comprising a body of reinforced cementitious material provided with 10 a pair of transverse ribs on its upper face whose end portions extend beyond the tie body and have grooves in their upper faces, suspension wires encircling the tie and passing across the grooves near their bottoms, 15 and track rail chairs in the grooves on the wires movably engaging the ribs.
2. A track tie comprising a body of reinforced cementitious material provided with a pair of transverse ribs on its upper face 20 whose end portions extend beyond the tie body and have grooves in their upper faces, divergent convex sheet metal reinforcing wings embedded in the ends of each rib, suspension wires encircling the tie and wings 25 and passing across the grooves near their bottoms, and track rail chairs in the grooves on the wires movably engaging the ribs.
3. A track tie comprising a substantially 30 rectangular metal main frame transversely wound with wire, a pair of divergent convex sheet metal reinforcing wings secured at their lower ends to the lower side members of the main frame near each end thereof, a templet above the main frame securing the 35 upper ends of the wings in spaced relation, a winding of suspension wires wrapped around the frame and each pair of wings, a hollow shell of cementitious material embedding the main frame, solid transverse ribs 40 in the shell enveloping the wings and suspension wires and having laterally extending ends with grooves in their upper faces which extend below the suspension wires and rail chairs in the grooves supported by 45 the wires and loosely secured to the sides of the ribs.
4. A track tie comprising a substantially 50 rectangular metal main frame transversely wound with wire, a pair of divergent, convex sheet metal reinforcing wings secured at their lower ends to the lower side members of the main frame near each end thereof, secondary reinforcing rods each bent between its ends in N-shape both above and below the frame, a U-shaped anchor plate in each bend of the rods adapted to maintain the rods in parallel spaced relation to the plane of the wire windings, a templet above 55 the main frame securing the upper ends of the wings in spaced relation, a winding of suspension wires wrapped around the frame and each pair of wings, a hollow shell of cementitious material embedding the main 60

frame, solid transverse ribs in the shell enveloping the wings and suspension wires and 65 having laterally extending ends with grooves in their upper faces which extend below the suspension wires, and rail chairs in the grooves supported by the wires and loosely secured to the sides of the ribs.

5. In a railway tie of cementitious material, means for yieldingly securing a track rail thereto comprising a pair of outwardly convex sheet metal wings secured at their lower ends in the base of the tie, a templet 75 connecting the upper ends of the wings, a layer of suspension wire wrapped around the wings and templet in spaced relation, a transverse rib of cementitious material integral with the body embedding the wings and 80 suspension wires and having a pair of grooves in its upper face parallel to the tie body extending below the suspension wires, and rail chairs in the grooves yieldingly supported by the wires and movably secured 85 to the sides of the ribs.

6. In a railway tie comprising a hollow shell of cementitious material and a metal reinforcing frame embedded therein, means for yieldingly securing a track rail thereto 90 comprising a pair of outwardly convex sheet metal wings secured at the lower ends to the lower member of the frame near its ends, a templet securing the upper ends of the wings in spaced relation above and outside the 95 main frame, suspension wires around the wings in parallel spaced relation bridging the space between the wings above the templet, a transverse rib of cementitious material integral with the tie body embedding the 100 wings and wires whose laterally extended ends have grooves in their upper faces parallel to the body of the tie which are crossed by the suspension wires, and a rail chair in each groove having a body supported by 105 the wires, depending arms adapted to movably engage indents in the rib sides, and a pair of rail retaining lugs on the upper face of the body.

7. A track tie comprising a substantially 110 rectangular metal reinforcing frame wound transversely by a double layer of wire, a pair of sheet metal convex wings secured by their lower ends to the lower side member of the frame near each end thereof, a templet 115 above the frame securing the upper ends of the wings in spaced relation, a cylindrical bearing rod on each end of the templet in parallel relation to the upper face of an adjacent wing, a suspension wire wound around 120 each pair of wings and templet bearing on the rods, N-shaped reinforcing rods, anchor plates engaging the bends of said rods adapted to maintain them in a plane parallel to the adjacent sides of the frame, a hollow 125 shell of cementitious material embedding the

main frame, solid transverse ribs in the shell enveloping the wings and suspension wires and having laterally extending ends with grooves in their upper faces which extend 5 below the suspension wires, and rail chairs in the gains supported by the wires and loosely secured to the sides of the ribs.

In testimony whereof I affix my signature in presence of two witnesses.

WILLIAM GABRIEL.
